UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

MEANS FOR AND METHOD OF MAKING LOCK WASHERS

Application filed March 23, 1931. Serial No. 524,453.

My invention relates to means for and drawings, wherein— methods of producing lock washers, and more particularly to apparatus and methods whereby lock washers of an improved pronged construction may be produced.

It is one of the primary objects of my present invention to provide a simple and improved mechanism, whereby pronged lock washers having oppositely disposed acute work engaging edges may be economically and expeditiously manufactured.

Another object of my invention is to provide a method and an apparatus for practicing same, whereby lock washers may be formed from flat spring stock by initially shearing said stock so as to provide acute corners on the prongs and then warping or deflecting said acutely formed prong to position work engaging corners or edges out of the plane of the washer body.

Still another object of my present invention is to provide an improved method of shearing flat stock, such as stock employed for making pronged lock washers, which consists in subjecting the stock to a shearing force in a direction which is inclined with respect to the plane of the stock and thereby producing prongs having oppositely disposed acute work engaging edges.

In addition to the method and apparatus for providing acutely formed lock washers, I also propose to provide a method and means whereby said acutely formed prongs may be progressively warped or twisted so as to present the acutely formed edges thereof in planes spaced from and substantially parallel with the plane of the washer body.

My invention also contemplates the provision of an improved helical punch and die arrangement, whereby the above method of producing lock washers may be effectively practiced.

It is also an object of my invention to provide improved means, whereby the above mentioned shearing and forming operations may be performed in automatic succession.

The foregoing and numerous other objects and advantages will be more apparent from the following detailed description when considered in connection with the accompanying

Figure 1 is a fragmentary elevational view of an apparatus, whereby my improved method of producing pronged type lock washers may be practiced;

Figure 2 is a transverse horizontal sectional view of my improved punch and die mechanism taken substantially along the line 2—2 of Figure 3;

Figure 3 is a central sectional view of the punch and die mechanism taken substantially along the line 3—3 of Figure 2, a strip of stock being shown in operative association therewith;

Figures 4 to 9 inclusive present an exploded view of my improved helical punch and die arrangement, Figure 4 disclosing the helical punch or male die section; Figure 5, the guide therefor; Figure 6, the spider which forms a part of the female die section; Figure 7, the section which cooperates with the spider to complete the female die; Figure 8, the sleeve which provides the support for the spider; and Figure 9, the ring upon which the entire female die section rests;

Figure 10 is a transverse sectional view of the male die section taken substantially along the line 10—10 of Figure 4;

Figure 11 is a plan view of the device shown in Figure 5;

Figure 12 is a plan view of the spider shown in Figure 6;

Figure 13 is a plan view of the female die section shown in Figure 7;

Figure 14 is an enlarged plan view of a strip of stock disclosing the successive forming operation in producing the washer by practicing my improved method;

Figure 15 is an enlarged perspective view of one of the forming members or dies, which is adapted to impart a progressive deflection or twist to the prongs of the washer;

Figure 16 is a side elevational view of a washer before the prongs thereof are deflected in response to the action of the device shown in Figure 15;

Figure 17 is an enlarged end view of one of the prongs of the structure shown in Figure 16;

Figure 18 is a plan view of a completed lock washer;

Figure 19 is a side elevational view of the washer of Figure 18; and

5 Figure 20 is an enlarged end view of one of the prongs of the washer of Figure 19, said view being shown in order to more clearly disclose structural characteristics of the acutely formed prong.

10 Referring now to the drawings more in detail, wherein like numerals have been employed to designate similar parts throughout the various figures, it will be observed that my invention contemplates the provision of a die mechanism, designated generally by the numeral 30, of improved practical construction, whereby my improved method of producing lock washers may be effectively practiced. In order to more clearly illustrate

15 20 a practical embodiment of my invention, I have disclosed said die mechanism in operative association with a suitable punch press, which I have designated generally by the numeral 32. This punch press 32 and a strip 25 feeding mechanism designated generally by the numeral 34, are disclosed and described in detail in the co-pending application of Carl G. Liljeberg, Serial No. 233,003, filed November 14, 1927. For the purpose of clear-

30 35 ly understanding the present invention, it will suffice to say that the mechanism 34, which is driven by means of a chain 36 coupled with the driving mechanism (not shown) for the punch press 32, includes a cam 38, which co-operates to effect reciprocation of an arbor 40, and this arbor is adapted to successively engage the apertured portions of the strip material 42 formed by the die mechanism 30. Thus by means of the mecha-

40 45 nism 34, the strip material is intermittently advanced from a supply reel 44 through the die mechanism 30, and the remaining portion of the strip is again received by a reel 46.

The die mechanism 30 includes a suitable punch member or support 48, which is adapted to be secured within the vertically reciprocable head 50 of the punch press 32, Figure 1. The punch member 48 carries a die block 52, and this block serves as a support for a plu-

50 55 rality of die members 54, 56, 58, 60, and 62, Figure 3. These die members are reciprocable within a suitable fixed guide plate 64, and vertical guide pins 66 serve to direct the vertical shifting of the punch member 48.

60 65 A lower fixed punch member or block 68 supports a die block 70, and this die block 70 serves as a mounting for the die elements or sections which are companion to the die members carried by the block 52, and are correspondingly designated by the numerals 54a, 56a, 58a, 60a, and 62a.

Consider, for example, that the strip material 42 is initially introduced between the upper and lower sections of the die mechanism 30. As the punch block 48 moves

downwardly, the punch element 54 causes an aperture 72 to be formed within the stock (see Figure 14). As the punch block 48 moves upwardly, the strip may be advanced to its next position, at which time the aperture, which was initially formed, will be positioned to receive the punch member or pilot 56. Upon the next advancement of the strip material, the initially formed aperture 72 will be positioned between the pilot 56 and the die or punch member 58. Upon the next advancement of said strip, the initially formed aperture 72 will be positioned immediately beneath the punch or die 58, the pilot 56 in this instance serving to accurately position the strip to be acted upon by the member 58.

Particular attention is directed to the punch member 58 which may be referred to as a male die section, said section being formed with a plurality of helically disposed punch elements 74, Figures 4 and 10. Spaces 76 presented between the punch elements 74 conform with the shape of the prong to be formed in the completed washer, said completed washer being shown in Figure 18. In this figure the annular body of the washer is designated by the numeral 78, and the prongs thereof by the numeral 80. The central lower portion of the male die section 58 is provided with a recess 82, and a hardened collar 84, Figures 3, 5, and 11, serves as a means for guiding the punch elements 74 during their reciprocable movement. This collar 84 is formed with helically disposed recesses 74a, which correspond in circumferential width to the width of the punch elements 74, and thus serve to guide said elements during their reciprocation. In this connection it will be noted that the upper end of the male die section 58 is rotatably supported within an anti-friction or ball bearing mechanism 86, said mechanism being carried by the die block 52, Figure 3. By this arrangement the male die section 58 is adapted to rotate in response to the reciprocation of the helical punch elements 74 within their companion helical guide ways 74a.

The female die section 58a, which is companion to the male die section 58, includes a 115 sleeve 88, Figures 3, 7, and 13, said sleeve being mounted within the lower die block 70. A plurality of helical grooves 90 are formed along the inner surface of the upper portion of the sleeve 88, and these grooves are 120 designed to receive the outer extremities of helically disposed teeth 92 of a spider 94, Figures 2, 6, and 12. It will be observed that when the spider 94 is lowered within the sleeve 88, spaces 96, Figures 2 and 12, presented between the spider teeth conform with the cross-sectional shape of and are adapted to receive the punch elements 74 of the male die section 58. Thus, as these punch elements 74 are moved downwardly into associ- 125

ation with a strip 42, sections of said strip are punched therefrom so as to provide spaces 98, Figure 14.

The helical disposition of the elements 74 and the helical disposition of the cooperative sides of the spider teeth 92 cause the stock to be sheared at an angle, thereby causing the resulting prongs 80 to be diamond-shaped in cross-section. In this connection 10 particular reference is made to Figure 17, wherein I have disclosed an enlarged view for the purpose of illustrating this inclined shearing action. It will be seen that the angles designated by the letter A in Figure 15 17 are acute angles and that the cross-section of the prong is diamond-shaped.

As the strip is successively advanced, it is brought into position between the forming members 60 and 60a. The member 60a is disclosed in perspective detail in Figure 15, and it will be apparent that the cooperative member 60 is similarly formed. These members are provided with teeth 100 which are so disposed as to impart the desired deflection or twist to the prongs 80. In the embodiment of the invention disclosed in the drawings, I desire to warp or deflect the prongs so as to present acute work engaging edges 102, Figures 18, 19, and 20 out of the plane of 30 the washer body 78, said edges lying in planes which are substantially parallel with the plane of said body portion. Obviously the exact surface contour of the teeth 100 will be dependent entirely upon the required 35 shape of the washer prong. In disclosing the teeth 100, I have not endeavored to accurately indicate the helical configuration of said teeth, but have merely presented a view which sufficiently approximates the exact 40 tooth configuration to enable a clear understanding of my present invention.

After the stock has been acted upon by the helical die member 58, it will appear as shown by the cut-outs included between the 45 bracket B, Figure 14. This cut-out will eventually be advanced into position beneath the punch 62, which serves to sever the outer extremities of the prongs 80 from the remaining portion of the stock, and 50 causes said completed washer to be ejected into a cylinder discharge opening 104, Figure 3.

From the foregoing it will be apparent that the strip material is advanced step by 55 step through the die mechanism, and during each actuation thereof a completed washer will be directed through the discharge opening 104. Thus my invention contemplates the provision of a method, whereby 60 washers having prongs of diamond-shaped cross-section may be formed in automatic succession from flat stock. The work engaging edges 102, as stated above, are acute 65 and lie in planes substantially parallel with the plane of the washer body 78, and by

having these edges formed acutely, their locking effectiveness when clamped between the surfaces of work pieces is materially increased. The described helical die arrangement provides a very convenient and effective means for imparting an angular shear to the stock, and by having the female die section which cooperates therewith, formed in two parts, namely, the part 88 and the spider 94, the problem of manufacture is 70 greatly simplified. That is to say, it is far more simple to provide helical grooves along the outer edge of the spider and companion helical grooves along the inner edge of the die member or sleeve 88, than it would be to 75 provide helical slots within a solid piece of material.

My improved helical punch 58 may be characterized as a multiple threaded screw-like body, in which thread elements, namely, 80 the helical punch elements 74, extend beyond one end of the core of the screw body. These extending portions are adapted to be received by companion internal threads provided in the die member 58a. It may further be 85 stated that this die member 58a has its core intact inasmuch as the spider 94 is mounted within the member 58a. I prefer to employ a helix angle not greater than 45 degrees. That is to say, the angular disposition of the 90 punch or thread elements 74 with respect to the axis of the punch 58 will ordinarily not exceed 45 degrees. However, my invention is by no means limited to any particular angular disposition.

While I have disclosed one specific embodiment of the die mechanism for imparting an angular or inclined shear to the flat spring stock, it should be understood that my invention is by no means limited to the specific 105 structure disclosed in the drawings, but is capable of other modifications and changes without departing from the spirit and scope thereof.

Having thus described my invention, what 110 I claim as new and desire to secure by Letters Patent is:

1. The method of producing lock washers from flat spring stock which consists in shearing said stock at an angle oblique with respect to the plane thereof so as to produce a plurality of washer prongs having acute work engaging teeth.

2. The method of producing lock washers from flat spring stock which consists in 115 successively shearing said stock at an angle oblique with respect to the plane thereof so as to produce a plurality of washer prongs having acute work engaging teeth, whereby lock washers may be produced in automatic 120 succession from a sheet of flat stock.

3. The method of producing lock washers from flat spring stock which consists in shearing said stock at an angle oblique with respect to the plane thereof so as to produce 130

- a plurality of washer prongs having acute work engaging teeth, and warping said prongs so as to position said acute work engaging edges out of the plane of the washer stock.
4. The method of producing lock washers from flat spring stock which consists in subjecting said stock to the shearing action of a plurality of helically disposed cutters so as to produce a plurality of annularly arranged cut-outs separating annularly disposed washer prongs having oppositely disposed acute edges, and deflecting said prongs so as to position said edges out of the plane of the washer stock.
5. In apparatus for producing lock washers from flat spring stock, a die mechanism including a plurality of cutters having shearing surfaces inclined with respect to the plane of the washer stock and adapted to follow a helical path for producing washer prongs having oppositely disposed acute edges, and means for deflecting said washer prongs so as to position said acute edges out of the plane of the washer stock.
6. In apparatus for producing lock washers from flat spring stock, a die mechanism including a plurality of cutters having shearing surfaces inclined with respect to the plane of the washer stock and adapted to follow a helical path for producing washer prongs having oppositely disposed acute edges, means for deflecting said washer prongs so as to position said acute edges out of the plane of the washer stock, and means for successively advancing stock acted upon by said die mechanism.
7. A die mechanism for producing lock washers and the like from flat spring stock including means having a plurality of annularly disposed helical cutters, and means companion to said helical cutters for effecting the shearing of a piece of flat spring stock when said cutters and companion means are relatively shifted.
8. A die mechanism for forming lock washers and the like from flat spring stock including a cylindrical member having a plurality of spaced peripheral cutters arranged helically with respect to the axis thereof, one extremity of said cutters lying in a substantially common plane and adapted to engage the surface of the work piece for producing apertures therein, and a cooperative die element for engaging the opposite surface of the work piece, said die element having helical ways companion to said helical cutters.
9. A die mechanism for forming lock washers and the like from flat spring stock including a cylindrical member having a plurality of spaced peripheral cutters arranged helically with respect to the axis thereof, one extremity of said cutters lying in a substantially common plane and adapted to engage the surface of the work piece for producing apertures therein, a cooperative die element for engaging the opposite surface of the work piece, said die element having helical ways companion to said helical cutters, and means for rotatably supporting one of said parts, whereby to permit of rotation occasioned in response to the helical disposition of the cutters.
10. A die mechanism for producing lock washers and the like including a support, a punch member mounted in said support, said member including a plurality of spaced cutter elements disposed at an angle with respect to the plane of the washer stock to be acted upon, and a die mechanism cooperatively arranged with respect to said punch elements, said die mechanism including a sleeve and a spider mounted therein for receiving said punch elements.
11. A die mechanism for producing lock washers and the like including a support, a punch member mounted in said support, said member including a plurality of spaced cutter elements disposed at an angle with respect to the plane of the washer stock to be acted upon, a die mechanism cooperatively arranged with respect to said punch elements, said die mechanism including a sleeve and a spider mounted therein for receiving said punch elements, and means for guiding said punch elements.
12. An apparatus for producing lock washers from flat spring stock, a screwlike element having external multiple threads, sections of said threads extending at one end beyond the core of said screwlike element, and a cooperative device having internal threads which are companion to the threads in the screwlike element, said internally threaded device having a core intact, and means for imparting relative axial movement to said screwlike element and said internally threaded device, whereby the extending portions of the external threads will register with the threads of the internally threaded device for the purpose set forth.

In witness whereof, I have hereunto subscribed my name.

CARL G. OLSON.
